Fig. 3.

Fig. 5.

Fig. 4.

Fig. 2.

Fig. 1.

FIG. 1 is a side elevational view of a golf club showing my new design.

FIG. 2 is a rear perspective view.

FIG. 3 is a top plan view.

FIG. 4 is a bottom plan view.

FIG. 5 is a fragmentary side elevational view.

The essential features of my design reside in the full lines portions shown, with the broken line portions of the shaft omitted from FIGS. 2 through 5 for convenience of illustration. The opposite side of FIG. 1 is substantially a mirror image thereof.

I claim:

The ornamental design for a golf club, as shown and described.
